ATHLETIC FOUL AUTOMATIC INDICATOR
Earl R. Jackson, 1851 Lomita Ave., Stockton, Calif.
Filed Aug. 28, 1961, Ser. No. 134,807
10 Claims. (Cl. 116—114)

This invention relates to the automatic indication of fouls in athletic events where the take-off or effort is made behind a straight restraining or scratch line and more particularly to the running broad jump, a standard event in track and field athletics. By nature of these events the athlete's approach is extremely rapid and many trials are made which often are very difficult for the official to judge fair or foul.

The prime object of my invention is to design a sturdy and compact device which can be easily attached to the far side of the "take-off" board and automatically indicates by oscillation of wings any contact made on the device.

Another object is to design a device which will automatically indicate fouls, thus eliminating the human factor in judging these events.

A further object is to design a foul indicator for any athletic event where the effort is made behind a straight scratch line.

A still further object is to design a device which in open athletic fields the external parts can quickly be removed and the housing boxes padlocked to prevent tampering with the internal mechanism.

Another object of the invention is to reduce fouling by the arrangement and contrasting color of the exterior parts of my indicator which thereby gives a clear cut delineation of the foul line.

Still another object of this invention is to glamourize the jump events, thus enhancing athlete and spectator interest.

A further object of the instant invention is the provision of means to instantaneously indicate to the spectators whether the trial is fair or foul.

With the above objects in view, this invention consists in the combination and arrangement of parts, hereinafter more fully described, illustrated in the accompanying drawings and more particularly pointed out in the appended claims, it being understood that changes may be made in the form, size, proportions, and minor details of construction, without departing from the spirit or sacrificing any of the advantages of the invention.

In the drawings:

FIGURE 1 is a plan view, partially broken away for illustrative clarity, of my athletic foul automatic indicator showing the body, housing box, partial contents and wing assemblies, the broken lines representing the official take-off board.

FIGURE 2 is an enlarged transverse cross-sectional view taken on the line 2—2 of FIGURE 1 showing portions of the device in the set position.

FIGURE 3 is an enlarged transverse cross-sectional view taken on the line 3—3 of FIG. 1 showing oscillation of the wings.

FIGURE 4 is an enlarged vertical cross-sectional view taken on line 4—4 of FIG. 1 showing the internal mechanism and foul-board.

FIGURE 5 is a fragmentary transverse cross-sectional view showing the foul board in locked position.

FIGURE 6 is a fragmentary view showing the means of detachment and rotation of the trigger-arm within the housing box.

FIGURE 7 is an enlarged elevational view showing the detachable wing assembly and supporting brace.

FIGURE 8 shows an exploded view of the attachment of the wing assembly to said brace.

FIGURE 9 is an end view of the wing assembly showing the supporting latch.

2

FIGURE 10 is an end view showing hasp with the latch rotated.

FIGURE 11 is an elevated view showing the hasp and padlock.

Referring now more particularly to the accompanying drawings in which I have shown the preferred embodiment of my invention, the letter B indicates an elongated box-like body comprising a floor or base 1, rectangular ends 2 and side walls 3. The top or foul-board 4 fits snugly inside three upper edges of the body, the far side wall being recessed at 5 the thickness of the foul-board as shown in FIGURE 2.

The foul-board 4 is composed of a metal plate 6 which gives rigidity, screwed by means 7 to a board 8 which is bevelled at 9 along the upper far edge to prevent the athlete from tripping. The above foul-board 4 construction readily allows replacement of the board 8 when the same is worn by shoe spikes. Underneath the metal plate 6 midway at each end is welded at right angles a plate 10 perforated at 11 to receive the end of the locking plate 12, described later.

Within the body B along each sidewall 3, a board 13 on edge, the same height as the far side wall 3 is secured to the base by screws 14. It is clearly shown in FIGURE 2 that these sideboards 13 and the far side wall 3 limit the depression of the foul-board 4. Near each end and in the middle of said side boards 13, holes 15 contain springs 16 which press the foul-board 4 upwards.

The L lever 17 oscillates on a pin 18 secured to the side board 13. This lever 17 is pin-connected at 19 to a rod 20 which passes through an aperture in the end wall 2. Holes 21 in the base 1 allow any water to escape.

Turning to the wing assemblies W-1 refers to the smaller and W-2 to the larger wing. Wings W-1 and W-2 are welded at right angles to each other, to sleeve rings 22 which oscillate on a rod 23. At the far end the rod 23 is welded to a right angled plate or bracket 24 hooked 25 underneath a plate 26 attached at right angles on top of brace 27 a continuation of the far side wall 3 of the housing box H. A pin 28 through the above plates holds the rod 23 in a stable position. A chain (not shown) attached to the bracket 24 and pin 28 prevents loss of the latter. A pin 29 near sleeve ring 22 keeps the wings from slipping off rod 23 when the latter is removed.

The sleeve ring 22 spring pressed at 30 keeps the sleeve ring at the near end lightly in contact with a latch 31 pin-connected at 32 to the edge of the hasp 33 (described later). The latch 31 has a hole 34 into which the rod 23 slips, the center of said rod being in exact line with the far edge of the foul-board 4. The latch 31 in contact with the housing H side-wall 3, passing through a slot in the housing lid 35 is locked in position when the housing lid is closed and when the latter is opened may be rotated down inside as shown in FIGURE 10.

The near side of the wing W-2 is painted white and all other visible parts of the device a distinctive color such as fluorescent orange give the athlete a clear cut delineation of the foul-line. On both sides of W-1 is painted in black the word Foul and on W-2, Fair, O.K., or the like (not indicated in the drawings). The plug 36 on the wing W-1 holds said wing horizontal as does the plug 37 on W-2 when the wings are oscillated. They also act as shock absorbers.

The housing H at each end of the body B is a continuation of the latter with an end wall 38 bearing a hinge 39 welded to a lid 35 which fits inside and flush with the upper edges of the housing H. Ledges 40 hold the lid 35 from being depressed. A hasp 33 welded to the far side wall 3 passes through a slot in the lid 35. A hole 41 allows the housing H to be padlocked such as by the lock 42, protecting the internal mechanism.

In housing H the projecting end of rod 20 is slotted at 43 and can be closed by a latch 45 pivotable about 44 over the pin 46 of the trigger 47. This arrangement allows said trigger 47 to be disconnected and rotated down inside housing H.

The trigger 47 pin-connected at 48 near the base 1 and normally urged in a counterclockwise direction about spring means 49, passes through a slot in the lid 35 the notch 50 holding down the wing W-1 which is slotted at 51. Note FIGURE 1. Spring 49 also pulls on the connecting rod 20 keeping the L lever 17 constantly in contact with the base 6 of the foul-board 4.

A peg 52 is attached to the base 1 surrounded by a detachable spring 53 which presses a plunger 54, which passes through the lid 35, against the wing W-1 with sufficient force to raise said wing to a vertical position when the trigger 47 is released. With the lid 35 open, spring 53 may be removed, allowing plunger 54 to drop flush with the lid 35.

Another method of spring-pressing wing W-1 is by spring 30 FIGURE 7. Both ends of the spring are turned at right angles, one end entered in a hole drilled in sleeve ring 22, the other end in bracket 24. Before inserting pin 28 twist bracket 24 in the direction wing W-1 turns.

A large pin 12 passes through end walls 38 and 2 into the aperture 11 where the pin is reduced to 1/2 round 55 limiting the rise of the foul-board 4 above the plane of the take-off board T as shown in FIG. 2. This raised feature plus the distinctive contrasting color of the foul board 4 clearly marks the foul line. The latter when depressed may be locked down when pin 56 is turned 180°. Washers 57 and cotter pins 58 on pin 12 prevent its lateral movement.

In operation the far side wall 3 of the body B is lag-screwed at 59 to the near side of the installed take-off plank T and pegs P driven into the ground, the top edges of the body B lying in the plane of the upper surface of the take-off plank T. When the athlete makes a fair jump from T no action takes place in the device, the vertical wings W-2 indicating Fair, O.K., or the like. If any part of the athlete's shoe projects over the scratch-line, the foul-board 4 is depressed which trips the triggers 47 releasing the horizontal wings W-1, spring-pressed, instantaneously rise to a vertical position indicating Foul. The wings are quickly reset with one hand.

It will thus be apparent that I have designed a simple and durable athletic foul automatic indicator which can be inexpensively manufactured, and which lends itself to use in several athletic events.

What I claim is:

1. An automatic foul line indicator for designating the violation of a foul line comprising a take-off board having an upper surface and having an edge substantially coincident with said foul line, a foul board having two ends, an upper surface, a lower surface and an edge substantially flush with said edge of said take-off board, means normally urging said foul board in an upward direction to raise said upper surface of said foul board slightly above said upper surface of said take-off board, a pair of indicator wings fixed at right angles to each other adjacent at least one end of said foul board, rod and sleeve means pivotally supporting said pair of wings about the vertex of said right angle, trigger means normally maintaining one of said indicator wings in a substantially horizontal plane while the other of said wings extends upwardly in a substantially vertical plane coincident with said foul line, lever means responsive to a depression of said foul board to release said trigger means and spring-tensioned means to pivot said indicator wings about said rod and sleeve means when said trigger means is released so that said other wing of each of said pairs is in a substantially horizontal plane and said one wing of each of said pairs extends upwardly in a substantially vertical plane.

2. An automatic foul line indicator in accordance with claim 1 wherein said foul board comprises an upper

5 wooden member detachably secured to a lower metallic member.

3. An automatic foul line indicator in accordance with claim 1 wherein a housing is provided adjacent one end of said foul board beneath said pair of indicator wings, said housing having a hinged lid with means defining openings therein, said trigger means and said spring-tensioned means passing through said openings when said automatic foul line indicator is operative and being retractable within said housing when said automatic foul line indicator is inoperative and means to lock said hinged lid to said housing.

4. An automatic foul line indicator in accordance with claim 3 wherein said rod and sleeve means is detachably supported above said housing.

5. An automatic foul line indicator in accordance with claim 1 wherein said trigger means includes a trigger member having two ends, one end of said trigger member being pivotally supported within said housing, the other end of said trigger member being notched and engageable over said one wing when said one wing is in said substantially horizontal plane and spring means fixed to said trigger member intermediate said ends to normally urge said notched end into engaging contact with said one wing.

6. An automatic foul line indicator in accordance with claim 1 wherein means are provided for limiting upward movement of said foul board, said means comprising a plate secured to, and depending from, said lower surface of said foul board, means defining an opening in said plate, a rotatably supported pin having an end portion extending through said opening, said end portion having a flat diametrical surface and a half-round circumferential surface and means to rotate said pin to selectively engage said flat surface and said half-round surface with said means defining said opening in said plate.

7. An automatic foul line indicator in accordance with claim 1 wherein an elongated box-like body is provided below said foul board, said body having an open upper end communicating with said bottom surface of said foul board and wherein said lever means comprises an L-shaped lever pivotally supported within said body, a portion of said lever in contact with said bottom surface of said foul board, a connecting rod having two ends, one end of said connecting rod pivotally secured to said lever at a point remote from said portion and the other end of said connecting rod detachably and pivotally secured to said trigger means.

8. An automatic foul line indicator in accordance with claim 7 wherein means are provided within said body limiting downward movement of said foul board.

9. An automatic foul line indicator in accordance with claim 1 wherein a pair of indicator wings fixed at right angles to each other is provided adjacent each end of said foul board, rod and sleeve means pivotally supporting each of said pairs of wings about the vertex of said right angles, trigger means normally maintaining one of each of said pairs of indicator wings in a substantially horizontal plane while the other of each of said pairs of wings extend upwardly in a substantially vertical plane coincident with said foul line, lever means responsive to a depression of said foul board to release each of said trigger means and spring-tensioned means to pivot each of said pairs of indicator wings about said rod and sleeve means when said trigger means is released so that said other wing of each of said pairs is in a substantially horizontal plane and said one wing of each of said pairs extends upwardly in a substantially vertical plane.

10. An automatic foul line indicator in accordance with claim 1 wherein at least all the visible parts of said indicator are of a bright color and said one wing is of a color which distinguishes therefrom.
